UNITED STATES PATENT OFFICE.

OTTO SOLDAN, OF BERLIN-SIEMENSSTADT, GERMANY, ASSIGNOR TO SIEMENS & HALSKE AKTIENGESELLSCHAFT WERNERWERK, OF SIEMENSSTADT, NEAR BERLIN, GERMANY.

HAND TELEPHONE.

Application filed September 11, 1925, Serial No. 55,641, and in Germany December 5, 1924.

For cheapening the manufacture of hand telephones for telephonic purposes it has already been proposed to construct the handle together with the housings for the reception of the telephone and the microphone of one single piece.

The invention aims at a further cheapening and is directed particularly to the easy accessibility of the internal parts of the hand telephone so as to allow a single assembling and good observation.

According to the invention this is achieved by the handle and its housings for the microphone and telephone consisting of two loosely connected halves which are separated in a longitudinal direction. By dividing in this manner a substantial cheapening of the compressed body is achieved, as this arrangement enables the use of a simplified pressing shape whereby a reduction of scrap is brought about and a simple embedding of the essential metal inserts is permitted. Moreover this dividing of the compressed body facilitates an accessibility and visibility of the inner parts which is impossible with the usual executions.

According to the invention the two parts of the compressed body are constructed of a compressed insulated composition which preferably is formed of artificial resin and paper, so that a greater tenacity than is usual in such insulating compositions is obtained.

A further simplification is brought about in accordance with the invention by the hollow space for the reception of the microphone there being formed at the front a speaking mouthpiece so that a simplified assembly is ensured for the mouthpiece without the use of special fixing means.

The drawing shows three views of an embodiment of the invention. Figure 1 is a front view of such a hand telephone. Figure 2 is the lower half of the compressed body with portions of apparatus attached thereto. Figure 3 depicts in a side elevation the hand telephone composed of two mutually connected halves.

The compressed body of the microtelephone comprising the two similar halves 6 and 9 forms the handle 1 at its central portion whilst oblique to this there are arranged the housings 2 and 3 for the telephone 4 and the microphone 5. A mixture of artificial resin and paper is employed as a material

for the compressed body. The two halves can, of course, also be made from any other insulating material suitable for die-casting. In one half (6) of the compressed body metal inserts 7 are embedded. These inserts make the conductive connection from the telephone 4 to the connecting cord 8 and at the same time increases the strength of the handle 1. The inserts 7 can be so proportioned that a definite total weight is given to the hand telephone.

As the inserts 7 penetrate into the space provided in the top covering half 9, it is guided in a satisfactory manner to coincide with the lower half. On the microphone side of the handle 1 the space provided in the housing 2 is closed to the outside by a walling 10 which serves as a mouthpiece for the microphone 5 so that special attaching means for the otherwise specially made portion of the mouthpiece are not necessary. The conductive connection from the inserts 7 to the telephone 4 takes place over the fastening screws 11 of the telephone case 4. Whilst the connection to the inserts 7 and the microphone casing 5 from the connecting cord 8 is effected over the connecting screws 12. As will be seen, the assembly of such hand telephones is exceedingly simple and enables the apparatus to be inspected for its effectiveness when in the open condition before the two halves 9 and 6 are joined together.

The two halves 6 and 9 are held together by means of three screws 13 which fit in holes of the top portion 9 and screw into inset metal portions 14 in the lower portion 6.

What is claimed is:

1. A hand telephone having a handle consisting of two detachably mutually connected halves, each half provided at its ends with hollow places for the reception of the microphone and receiver.

2. A hand telephone having its handle provided at its ends with hollow places for the reception of the microphone and receiver, said handle consisting of two detachable mutually connected halves, said handle formed of insulating material and the end for receiving the microphone being shaped to form a mouthpiece.

3. A hand telephone having its handle provided at its ends with hollow places for

- the reception of the microphone and receiver, said handle consisting of two detachable mutually connected halves, conductive elements partially embedded in one of said 5 halves for connecting the microphone and receiver to a connecting cord, said connected halves forming the sole means for holding all of said apparatus in position.
4. In a hand telephone having its handle 10 separable into two detachable halves having their ends provided with openings for the reception of a microphone and a receiver, rigid conductive elements embedded in one of said halves and penetrating the other 15 half to guide it in so that the two halves coincide in definite fixed relation to each other.
5. A hand telephone having its handles 20 separable longitudinally into two halves, one half containing hollow spaces for the reception of the microphone and receiver and having conductive elements embedded therein, the other half containing openings fitting around said apparatus, and means for de-
- tachably fastening said second half to said first half. 25
6. In a hand telephone, an insulating handle separable into two detachably mutually connected halves provided at their ends with hollow places for the reception of the microphone and the receiver, conductive elements embedded in one of said halves for connecting the receiver to a connecting cord, said receiver being fastened to and held in said handle by said conductive elements. 30
7. A hand telephone having its handle made of insulating material and provided at its ends and through its center with hollow places for the reception of the microphone, receiver and conductive elements, 35 said handle consisting of two detachable mutually connected halves for insulating and fastening said apparatus together as a unit. 40
- In witness whereof, I hereunto subscribe my name this 20th day of August, A. D. 45 1925.

OTTO SOLDAN.
